UNITED STATES PATENT OFFICE.

FREDERIK G. WHITTINGTON, OF EVANSTON, ILLINOIS, ASSIGNOR TO STEWART-WARNER SPEEDOMETER CORPORATION, OF CHICAGO, ILLINOIS, A CORPORATION OF VIRGINIA.

THERMOSTATIC SWITCH FOR TEMPERATURE INDICATORS.

Application filed April 20, 1922. Serial No. 555,777.

To all whom it may concern:

Be it known that I, FREDERIK G. WHITTINGTON, a citizen of the United States, having residence in Evanston, in the county 5 of Cook and State of Illinois, have invented certain new and useful Improvements in Thermostatic Switches for Temperature Indicators, of which the following is a specification, reference being had to the accompanying drawings, forming a part thereof.

This invention relates to a temperature indicator of the same general type as that shown in my copending application, Serial No. 444,134, filed February 11, 1921, and its 15 object is to provide an improved form of thermostatically operated switch for such apparatus. It consists of certain features and elements of construction hereinafter described and shown in the drawings as indicated by the claim.

In the drawings:

Figure 1 is a somewhat diagrammatic perspective view of a portion of a motor vehicle showing a thermostatically operated 25 temperature indicator associated with the engine thereof.

Figure 2 is a detail section taken as indicated at the line 2—2 on Figure 1.

Figure 3 is a vertical sectional view of 30 the thermostatic switch device, section being taken through the casing so as to reveal the working parts within.

Figure 4 is a fragmentary detail section taken similarly to Figure 3 to show a modified construction.

In the drawings, the engine of the motor vehicle is indicated at 1 and the signal device by which the driver is warned or advised of 40 temperature conditions in the engine is shown at 2 as conveniently mounted on the radiator cap. It may be understood that the signal device, 2, includes two incandescent electric lamps, 3 and 4, which are selectively lighted by the thermostatic device 45 mounted within the casing, 5, which is secured against a wall of the engine as shown in Figure 1. Heat insulating material, 6, serves to confine the engine heat within the casing, 5, and permit it to act upon the mechanism housed in the inner chamber, 7; any suitable form of clamping bracket, 8, is provided for holding the casing, 5, in position upon the engine. As seen in Figure 3, the device includes three binding posts for

electrical connections at 9, 10 and 11. The 55 lamps, 3 and 4, are both grounded at one side of their circuit and are connected respectively by suitable wires to the binding posts, 10 and 11, as shown by the wiring diagram in Figure 3.

Also protruding from the casing, 5, there is shown a post or support, 12, which carries within the chamber, 7, the cylindrical conductor sleeves, 13 and 14, secured upon its stem portion, 15, which may be a separate 60 part as shown driven into the lower end of the part, 12. If the stem, 15, is a metallic member it will be fully insulated from the conductors, 13 and 14. Figure 3 also shows on said stem, 15, a sleeve, 16, of insulating 65 material. The upper conducting sleeve, 13, is electrically connected by a spring contact member, 17, with the binding post, 10, and thence with the lamp, 3; the lower sleeve, 14, is similarly connected by a spring 70 contact, 18, with the binding post, 11, and thence with the lamp, 4.

The spirally coiled thermostat, 19, is mounted with its inner end fixed in a bracket, 9^a, supported by the binding post, 9, and in electrical contact therewith, while the free end of the thermostatic member, 19, carries a bifurcated contact brush, 20, whose arms embrace the insulating sleeve, 16, so long as the engine, 1, remains cold but which 75 are moved downwardly, first for contact with the conductor sleeve, 13, as the engine warms up to a normal running temperature. If the engine temperature exceeds a safe 80 limit the thermostat, 19, will uncoil still 85 further swinging its contact arms, 21, down upon the conductor cylinder, 14. Since the binding post, 9, which is electrically connected through its bracket, 9^a, with the thermostatic member, 19, and brush member, 20, is wired to one side of the battery 21, the other side of the battery being grounded, the contact of the brush, 20, with the cylinder, 13, establishes a circuit through the 90 lamp, 3, for lighting it to indicate normal 95 working temperature of the engine. When a safe working temperature is exceeded the brush, 20, is moved off the cylinder, 13, and onto the cylinder, 14, thus extinguishing the 100 light, 3, and lighting the lamp, 4, to give the 105 proper warning to the engine operator. The lamps, 3 and 4, may be arranged in any desired manner for display, as for example

5 by having different colored bulbs or being provided with differently colored screens through which their light is visible, or simply by being located at different points in the frame of the signal head, 2 so that they can be readily distinguished from each other.

10 If the signal is intended primarily to warn the operator of excessive temperature there is no need to indicate the cooling of the engine below its normal safe working temperature; therefore when this occurs the contact brush arms, 20, are permitted to swing onto the insulating sleeve, 16, so that neither 15 lamp will be lighted. The thermostatic movement in this direction is arrested by contact of a stop button, 22, which is conveniently carried on the rivet which secures the brush, 20, to the thermostat member, 19; 20 as this happens to strike against the binding post, 10, it is necessary to make the button, 22, of insulating material to prevent completing a circuit at this point and lighting the lamp, 3.

25 For determining accurately the engine temperature at which the danger signal lamp, 4, is to be lighted, the post, 12, carrying the contact sleeves, 13 and 14, is adjustable bodily in axial direction which is 30 substantially the direction in which the arms of the contact brush, 20, move. Said post, 12, is threaded at 23 to engage in a threaded bushing, 24, fixed in the casing so that by 35 turning the knurled head, 25, the post may be moved up or down in the casing. The lower end portion is guided by a bracket, 26, apertured to encompass the sleeve, 14. A detent spring, 27, is preferably provided bearing against the roughened surface of the

knob, 25, for holding the post at any position of adjustment.

If it is preferred to keep the lamp, 3, lighted throughout the entire range of temperature below the upper limit of safety, the insulating sleeve, 16, may be dispensed with as shown in Figure 4, in which only two contact cylinders, 13^a and 14^a, are carried on the reduced stem, 15, of the adjusting post, 12. In this case the stop button, 22^a, need not be of insulating material since the 60 arms of the brush, 20, remain in contact with the sleeve, 13^a, at the upper limit of their travel, and the lamp, 3, is to be kept lighted unless the entire device is thrown out of service by a circuit-breaking switch, 65 not shown.

I claim:—

A thermostatic switch device comprising a member responsive to temperature change, a contact brush movable thereby, a plurality of contacts insulated from each other, but closely adjacent for immediately successive engagement by the brush, said brush having a further range of movement beyond one end 65 of said contacts for completely opening the circuit, and means for adjusting said contacts together as a unit along the path of the brush together with fixed spring conductors mounted for sliding engagement with the contacts respectively for connecting them into different electric circuits and maintaining such connection throughout the range of adjustment of the contacts.

In testimony whereof, I have hereunto set my hand at Chicago, Illinois, this 17th day 70 of April, 1922.

FREDERIK G. WHIFFINGTON.
